BUFFER DEVICE FOR FIREARMS

Frederick L. Humeston, Hamden, Conn., assignor to The High Standard Manufacturing Corporation, New Haven, Conn., a corporation of Connecticut

Application June 25, 1946, Serial No. 679,246

5 Claims. (Cl. 42—75)

1

The present invention relates in general to firearms and more particularly to improved means for absorbing recoil shocks between the receiver and the complementary stock of the firearm.

In the past, efforts have been made to absorb the recoil shocks or stresses incident to the discharge of a firearm by providing, for example, integral abutments on the inner walls of the recess of the stock against which the depending portion of the receiver was adapted to seat, the force of the recoil being transmitted by the receiver to the wall-abutments of the stock. This construction has not, however, proved altogether satisfactory inasmuch as the recoil forces were thus applied to the stock adjacent the relatively-thin walls thereof which frequently caused these walls to split.

One of the objects of the present invention is to provide a firearm structure having a superior construction and arrangement of parts whereby the connection of a receiver and a stock is such as to eliminate splitting of the stock by recoil shocks or stresses incident to the discharge of the firearm.

A further object of the present invention is to provide a superior firearm construction wherein means is provided within the receiver-cavity of a stock arranged to transmit the rearward recoil shock, in such a manner as to relieve the walls of the stock from shocks or stresses and effectively preclude the occurrence of splitting.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a view of the central portion of a firearm embodying the recoil-transmitting means of the present invention and shown partly in side elevation and partly in vertical central-longitudinal section;

Fig. 2 is a horizontal sectional view taken on line 2—2 of Fig. 1;

Fig. 3 is a broken view partly in side elevation and partly in vertical central-longitudinal section of the central portion of the stock, including the recoil-transmitting means;

Fig. 4 is a horizontal plan view of Fig. 3;

Fig. 5 is a transverse sectional view taken on line 5—5 of Fig. 3;

Fig. 6 is a perspective view of the improved shock-transmitting means of this invention; and

2

Fig. 7 is a broken side elevation of the receiver and fire-control mechanism of the firearm detached from the stock.

Referring to the drawings, the latter show an exemplary embodiment of the invention as used in a firearm of the type comprising a one-piece stock, shown generally at 10, having an open recess 11 extending longitudinally thereof. The recess 11 is substantially rectangular in cross section, as shown in Fig. 5, and comprises a closed rear end-wall 12, spaced parallel side-walls 13 and a bottom or floor 14. Since the recess 11 must be made wide enough to accommodate the receiver and fire-control mechanism hereinafter described, the recess 11 is relatively wide as compared to the over-all width of the stock, the walls of the latter adjacent the recess 11, being relatively thin. The floor 14 is provided with a suitable aperture 15 which extends from the rear wall 12 of the recess forwardly, and is adapted to accommodate the trigger-arm 16 of the fire-control mechanism, the latter being indicated generally at 17 in Figs. 1 and 7. Forwardly of the longitudinal slot 15 is a second longitudinal slot 18 in the floor 14 which is arranged to permit access to the rear end of the tubular-magazine 19 of the firearm, for loading the latter. The usual trigger-guard 20 is secured to the underside of the stock adjacent the aperture 15.

The longitudinal open recess 11 of the stock is adapted to accommodate the barrel 21, fire-control mechanism 17 and the receiver, the latter being indicated generally at 22 and comprising a rearwardly-extending tubular member 23 integral with or otherwise secured to the rear end of the barrel 21; and a frame-member or block 24 rigidly secured as, for example, by a welded or brazed joint, to the tubular member 23, the barrel 21, fire-control mechanism 17 and receiver 22 all being assembled as a unit in the recess 11 of the stock, and held securely therein by fastening-means comprising, in general, an assembly-screw 25 mounted in the underside of the stock and threadedly engaged in a stanchion 26 formed integrally or otherwise secured to the receiver forwardly of the block 24. Supported at its rear end on the frame-member or block 24 and at its forward end by the stanchion 26, is a sheet-metal cover 27 which is substantially U-shaped in cross section, and adapted to enclose the usual cartridge-carrier and safety-mechanism of the firearm. The above-described structure is typical of the one-piece takedown type of firearm, the minute details of which are immaterial to a full disclosure of the present invention.

Referring now to Fig. 1, when the barrel 21, fire-control mechanism 17 and receiver 22 are assembled in the aperture 11 of the stock, the rear end of the receiver, and in particular the rear end 28 of the block 24 thereof, is spaced forwardly of the rear wall 12 of the slot, as shown in Fig. 2. Mounted in the space between the rear wall 12 of the recess and the rear end 28 of the receiver-block 24, is the improved means of this invention for transmitting the rearward recoil shock and stresses incident to the discharge of the firearms, to the rear wall 12 of the recess in such a manner that none of the forces of recoil are applied to the adjacent relatively-thin walls of the stock, substantially all of the rearward recoil force being transmitted in a direction substantially parallel to the longitudinal axis of the stock and hence absorbed by the relatively-thick pistol-grip portion thereof, of which the rear wall 12 of the recess 11 constitutes an abutting face.

The force-transmitting means is shown generally at 29 in Fig. 6 and comprises a substantially-U-shaped relatively-stiff sheet-metal member having a base-portion at its rear end comprising a substantially-vertical transverse wall 30; and a pair of spaced parallel arms comprising substantially-vertical forwardly-extending walls 31. The bottom edges of the latter and of the base-portion 30 are in the same horizontal plane and are adapted to seat squarely on the floor 14 of the recess 11 in the stock, as shown in Fig. 5. The vertical dimensions of the forward ends of the forwardly-extending arms or walls 31 are greater than the vertical dimension of the transverse wall 30, the upper edge of the latter being blended into the upper edges of the walls 31 by a flat 32 and radius 33. The increased vertical dimensions of the side walls 31 provide increased stability and may also serve to distribute over a relatively-large area and hence to dissipate any forces acting against the thin side walls of the stock. Moreover, the reduced height of the rear end portion of the member 29 provides for the accommodation of the elements of the fire-control mechanism. The rear end or base-portion 30 of the force-transmitting member 29 is a substantially-planar vertical wall which is adapted to abut against the rear end-wall 12 of the recess 11. The arms or side walls 31 of the member 29 are adapted to extend forwardly closely adjacent the corresponding inner walls 13 of the recess 11 which, as shown in Fig. 5, are virtually planar surfaces. The forwardly-extending walls 31 of the member 29 are, however, not planar surfaces but each is provided with longitudinal stiffening-means which, as shown in Figs. 1 and 3, may be located in the lower half of the member 29 and comprises, in the present embodiment, an inwardly-projecting longitudinal undulation rib or fold 34 extending from a point adjacent the rear end-wall 30 of the member 29 forwardly to the forward end 35 thereof. As indicated in Figs. 2 and 5, each stiffening-means or rib 34 is flared inwardly adjacent its forward end 35 so as to provide a substantially-bell-shaped or conical end-portion 36. This construction is preferred in order that when the recoil-transmitting member 29 is mounted in the recess 11 of the stock, between the rear wall 12 of the recess 11 and the rear end 28 of the receiver-block 24, the forward ends 35 of the walls 31, and in particular of the bell-shaped portions 36 of the stiffening-ribs 34 will engage a relatively-large area of the rear end 28 of the receiver-block 24, the areas of engagement being

near the longitudinal center line of the receiver-block 24 and on opposite sides thereof. It is to be particularly noted that the forward ends 35 of the walls 31 and stiffening-ribs 34 engage firmly against the rear end 28 of the receiver-block 24 and that there is no abutting engagement of the walls 31 and stiffening-ribs 34 with the relatively-thin-walled casing 27 of the receiver. The force-transmitting element 29 is adapted to be secured in the recess 11 of the stock by fastening-means which may comprise a brad 37 or the like, adapted to project through an aperture 38 in the rear wall 30 of the member 29 into the rear end wall 12 of the recess 11.

15 Although the stiffening-means 34 of the present embodiment has proven satisfactory both from the standpoint of economy of manufacture and efficiency in operation, it will be understood that the stiffening-means may take other equivalent forms, and that the general shape and proportions of the member 29 may be varied to correspond to the available space in any particular firearm.

It will be readily apparent from the foregoing 25 description and drawings, that when the recoil-transmitting element 29 is assembled in the recess 11 of the stock, as shown in Figs. 1 and 2, the member 29 fits substantially snugly between the rear end-wall 12 of the recess 11 and the rear end 30 28 of the receiver-block 24, and hence the rearward-recoil force incident to firing the gun will be transmitted from the receiver-block 24 to the abutting edges 35 of the walls 31 and stiffening-ribs 34 of the member 29, and by the latter in 35 a substantially-longitudinal direction parallel to the longitudinal axis of the stock to the rear wall 12 of the recess. In this manner and by this means, the relatively-thin side walls of the stock adjacent the recess 11 are relieved of all shock or stress, thus effectively precluding the possibility of splitting the stock.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are 45 intended to be embraced therein.

I claim:

1. A firearm structure including in combination: a stock having an interior vertical longitudinal recess therein provided with a rear end-wall; a receiver-member arranged to seat in said recess; and recoil-transmitting means comprising a U-shaped sheet-metal member mounted in said recess, said member abutting at its base against the rear end-wall of said recess and having forwardly-extending arms each provided with an inwardly-projecting rib extending longitudinally thereof, the forward end of each rib being arranged to abut the rear end of said receiver-member to transmit the rearward recoil shock of said receiver-member to the rear end-wall of said recess.

2. A firearm structure including in combination: a stock having an interior vertical longitudinal recess therein provided with a rear end-wall; a receiver-member arranged to seat in said recess; and recoil-transmitting means comprising a U-shaped sheet-metal member mounted in said recess, said member abutting at its base against the rear end-wall of said recess and having forwardly-extending arms, each arm having

an inwardly-projecting stiffening-element extending longitudinally thereof, the forward end of each stiffening-element being arranged to abut the rear end of said receiver-member on opposite sides thereof to transmit the rearward recoil shock of said receiver-member to the rear end-wall of said stock.

3. A firearm structure including in combination: a stock having an interior vertical longitudinal recess therein provided with a rear end-wall; a receiver-member arranged to seat in said recess; recoil-transmitting means comprising a U-shaped sheet-metal member mounted in said recess, said member abutting at its base against the rear end-wall of said recess and having forwardly-extending arms, each arm having an inwardly-projecting fold extending longitudinally thereof, the forward end of each fold being arranged to abut the rear end of said receiver-member on opposite sides thereof to transmit the rearward recoil shock of said receiver-member to the rear end-wall of said stock; and means engaged in the base of said U-shaped member to secure the latter to the rear end-wall of said recess.

4. A firearm structure including in combination: a stock having an interior vertical longitudinal recess therein provided with a rear end-wall and a base-portion; a receiver-member arranged to seat in said recess; and recoil-transmitting means mounted in said recess and comprising a U-shaped member having a transverse base-portion arranged to abut against the rear end-wall of said recess and a pair of spaced parallel arms extending forwardly therefrom and supported freely on the said base-portion of said recess in juxtaposition to the respective side walls thereof, the forward free ends of said arms

being arranged to abut against the rear end of said receiver-member at opposite sides thereof respectively to transmit the force of recoil of said receiver to the rear end-wall of said recess.

5. In a one-piece takedown firearm, the combination with a one-piece stock having a recess provided with a rear end-wall and a base-portion; of a receiver arranged to enter said recess, said receiver having a rear shoulder; and a recoil-transmitting means mounted in said recess and comprising a unitary U-shaped sheet-metal member having a transverse base-portion arranged to engage against the rear end-wall of said recess, and a pair of spaced parallel arms bent up from the transverse base-portion of said member so as to extend forwardly therefrom, said arms being supported freely on the said base-portion of said recess in juxtaposition to the respective side walls thereof, the forward free ends of said arms being arranged to abut against the rear shoulder of said receiver on opposite sides thereof respectively to transmit the force of recoil of said receiver to the rear end-walls of said recess.

25 FREDERICK L. HUMESTON.
